US0D1006237S

(12) **United States Design Patent** (10) Patent No.: **US D1,006,237 S**
(45) Date of Patent: **** Nov. 28, 2023**

(54) **KNEE BANDAGE**

(71) Applicant: **Bauerfeind AG**, Zeulenroda-Triebes (DE)

(72) Inventor: **Hermann Rokitta**, Ruhr (DE)

(**) Term: **15 Years**

(21) Appl. No.: **35/513,912**

(22) Filed: **Sep. 29, 2021**

(80) **Hague Agreement Data**

Int. Filing Date: **Sep. 29, 2021**

Int. Reg. No.: **DM/216664**

Int. Reg. Date: **Sep. 29, 2021**

Int. Reg. Pub. Date: **Apr. 1, 2022**

(51) **LOC (14) Cl.** **24-04**

(52) **U.S. Cl.**

USPC **D24/190**

(58) **Field of Classification Search**

USPC D24/188-192; D29/121.1

CPC A61F 2005/0176; A61F 5/0123; A61F

13/085
